UNITED STATES PATENT OFFICE.

CHARLES A. GLOEKLER, OF PITTSBURG, PENNSYLVANIA.

DOOR.

No. 851,879.

Specification of Letters Patent.

Patented April 30, 1907.

Application filed January 23, 1906. Serial No. 297,525.

To all whom it may concern:

Be it known that I, CHARLES A. GLOEKLER, a citizen of the United States, residing at Pittsburgh, in the county of Allegheny and State of Pennsylvania, have invented new and useful Improvements in Doors, of which the following is a specification.

My invention pertains to the doors of the kind that are equipped at their lower ends with vertically movable strips, springs tending to raise said strips, and devices for forcing the strips downward against the action of the springs when the doors are closed; and it consists in the peculiar and advantageous door for cooling or refrigerating chambers, herein-after described and claimed, which door and the mechanism for assuring downward movement of the vertically movable strip when the door is closed and upward movement of said strip when the door is opened are constructed with a view of withstanding the rough usage to which the doors of cooling or refrigerating chambers are ordinarily subjected.

In the accompanying drawing, forming part of this specification: The figure is a perspective view of a refrigerating or cooling chamber and a hinged door provided with my improvements.

Referring by letter to the said drawing: A is the door opening of a refrigerating or cooling chamber. B is a horizontally swinging door, hinged at a to a casing upright b at one side of the opening A, and C is a vertically and rectilinearly movable strip, preferably of wood, rabbed as indicated by c so as to rest partly at the outer side of the lower portion of the door and partly between the lower end of the door and the floor, as shown. On its inner side the said strip C is provided with a packing strip D, of felt, canvas or other suitable material, which extends from its rabbed portion to a point below its lower edge so as to bear against the floor when the said strip C is depressed.

E are brackets connected to the outer side of the lower portion of the door and having outwardly extending studs d.

F are slotted straps fixedly connected to the strip C and receiving the studs d and secured on said studs by nuts e.

G are brackets secured to the face of the door at a point above the brackets E, and H are crank arms fixed on a rock-shaft I which is journaled in the brackets G. Between the crank arms H and the straps F

links K are interposed so as to assure the strip C moving vertically when the shaft I is rocked in one direction or the other. The crank arms H are fixed to the rock-shaft I through the medium of set screws f which bear in sleeves g of the crank arms and against the said rock-shaft, and from this it follows that the position of the crank arms, relative to the rock-shaft, may be changed whenever it is necessary to compensate for wear of the packing strip D or any other part of my improved mechanism.

In addition to the elements enumerated, the rock-shaft I is provided with a lever arm L. This lever arm is adjustably fixed by a set screw h on one end of the shaft I in position to be engaged by a tappet M connected to the outer side of the chamber wall, and hence it will be apparent that when the door is closed, the shaft I will be rocked outward and downward and the straps F will be moved downwardly on the studs d so as to crowd the strip C and its packing against the floor and in that way preclude the passage of air through the space between the lower end of the door and the floor. When the door is swung open, the lever arm L is carried away from the tappet M with the result that the strip C is left free to be raised so as not to render difficult the operation of moving the door to its fully opened position.

In order to raise the strip C when the same is released as stated, I provide the tractile spring N which is connected at one end to one of the crank arms H and at its opposite end to a hook P held by a nut Q to a bracket R on the face of the door. The said spring N is placed under tension when the strip C is depressed by the coöperation of the lever arm L with the tappet M, and from this it follows that when the lever arm is moved away from the tappet the spring will tend to contract and by so doing will raise the strip C and the appurtenances thereof. The connection of the hook P to the bracket R is preferably an adjustable one, as illustrated, so that the tension of the spring N may be readily regulated to suit different conditions.

It will be gathered from the foregoing that my improved mechanism is simple, compact and well adapted to withstand the usage to which such mechanism is ordinarily subjected. It will also be gathered that my said mechanism is readily applicable to a door without entailing change in the construction thereof, and that proper adjustment of the parts to

take up wear may be effected without the necessity of employing skilled labor. It will further be appreciated from the foregoing that while the strip C will be crowded against the floor when the door is closed with a view of preventing the passage of air between the lower end of the door and the floor, yet when the door is opened the floor is left free of obstruction so that trucks and the like may be readily rolled into and out of the refrigerating or cooling chamber.

With a view of preventing the heavy door usually employed from sagging and interfering with the proper operation of the strip C and the parts connected therewith, I provide the hanger S illustrated at the upper end of the drawing. The said hanger S comprises a bracket m connected to the wall of the chamber and having an upwardly extending post p, a rod section q pivoted on said post and arranged to swing horizontally, a rod section r connected through the medium of a fixture s to the door B, and a turn-buckle t disposed between and adjustably connecting the rod sections q and r. Through the medium of the turn-buckle t, the rod of the hanger S may be made as taut as desired, and when the said rod is in the proper state it will assist materially in sustaining the weight of the door and preventing sagging thereof.

The straps F are guided by the studs d and move against the smooth faces of the brackets E, and hence it will be observed that the vertical movements of the said straps may be accomplished with the expenditure of but little force.

I claim:

The combination of a door casing, a sta-

tionary tappet arranged on one of the uprights of the casing, a swinging door hinged to the other upright of the casing, brackets connected to the lower portion of the outer side of the door and having studs, a vertically movable strip arranged at the lower end of the door, straps fixed to and extending upward from the said strip and having vertically slotted portions loosely receiving the studs of the brackets, nuts retaining said straps on said studs, brackets secured to the outer side of the door at points above the first mentioned brackets, a rock-shaft journaled in the upper brackets and having crank arms and also having a lever arm; said lever arm arranged to be engaged by the stationary tappet on the closing of the door, links connecting the said crank arms of the rock-shaft and the straps on the strip, a bracket connected to the outer side of the door at a point above the brackets in which the rock-shaft is journaled, and having a vertically disposed aperture, a hook having a threaded stem extending loosely through the aperture of the bracket, a nut mounted on said threaded stem of the hook, and a tractile spring extending directly between and connected to one crank arm of the rock-shaft and the said hook, whereby when the lever arm is engaged by the stationary tappet said spring will be expanded.

In testimony whereof I have hereunto set my hand in presence of two subscribing witnesses.

CHARLES A. GLOEKLER.
